UNITED STATES PATENT OFFICE.

ALFRED TROSCH, OF ROCHESTER, NEW YORK, ASSIGNOR TO CONSOLIDATED MACHINE TOOL CORPORATION OF AMERICA, OF ROCHESTER, NEW YORK, A CORPORATION OF DELAWARE.

RAIL CLAMP.

Application filed July 18, 1927. Serial No. 206,560.

This invention relates to a rail clamp to hold a railway truck in predetermined position upon the track.

The principal object of the invention is to provide an efficient and simple clamping mechanism for anchoring a truck to a railway track so as to prevent movement of the truck.

Another object of the invention is to provide a form of clamping mechanism which can be quickly and easily tightened or released so that the truck may be moved along the rails when desired.

A further object of the invention is to provide a form of clamping mechanism which can be moved easily to an ineffective position to permit the entire truck to be lifted bodily off of the rails.

Still another object of the invention is to provide a simple form of clamp which requires a minimum amount of time and effort to move it from effective to ineffective position.

A still further object of the invention is to provide a simple and efficient mechanism for tightening several clamps simultaneously.

With these and other ends in view, the invention comprises the structure and combination of parts which will appear more clearly from the following description when read in conjunction with the accompanying drawings, the novel features being pointed out in the claims following the description.

In the drawings:

Figure 1 is a plan view of a truck adapted to run on railway rails, showing one possible embodiment of my invention applied thereto;

Figure 2 is a longitudinal section taken approximately along the line 2—2 of Figure 1;

Figure 3 is a transverse section taken approximately along the line 3—3 of Figure 1;

Figure 4 is an enlarged transverse sectional view through one of the clamps showing it in effective position;

Figure 5 is a section along the line 5—5 of Figure 4 showing the clamp in effective position, and

Figure 6 is a view similar to Figure 5 showing the clamp in ineffective position.

In machine shops and other factories, it is customary to mount certain machine tools upon small railway trucks. A large piece of work, such as a girder or a long bed plate, may be set up parallel to a convenient railway track,

and the machines for working upon the same (such as riveters or milling machines or any other devices), being mounted upon trucks, may be moved back and forth along the track so as to operate in different positions along the article being worked upon. When one of these machines is operating upon the work, it is evident that the truck upon which it is mounted must be held rigidly in place and kept from moving along the track. To this end, suitable clamps may be employed for clamping the truck to the rails, which clamps must be capable of being tightened to hold the truck firmly in any desired position, and must also be able to be loosened easily to permit the truck to be moved along the track to another position. At the same time, it is often necessary to lift these trucks bodily off the track in order to move them around an obstruction on the track to a new location without loss of time, when it is impossible to move the truck along the track in the usual manner. The clamps for holding the truck in position must therefore be of such a nature that they will not interfere with the truck being lifted vertically off the rails.

This application shows one possible embodiment of clamping mechanism designed to fulfill these conditions. It is to be understood, however, that this clamping mechanism and the various parts thereof are not limited in application to trucks of the kind mentioned above for carrying machinery, but may be applied to any other form of truck or vehicle running on railway rails whenever it is desired to hold such truck or vehicle rigidly upon the track.

In the embodiment of the invention shown in the drawings, the truck may consist of a main body or frame 11 provided with suitable wheels 12 for running upon railway rails 13. Upon this truck may be mounted any desired machine or tool, a part of which is represented diagrammatically by the numeral 14 in Figures 1 and 2. A truck of this kind may be moved along the track by hand or it may be provided with power means for moving it. If such power means is desired, one of the axles, such as 15, may be provided with a worm wheel 16 driven by a worm 17 on a shaft 18. This shaft may be driven by gearing 19 and 20 operated by a suitable motor 21.

The clamping mechanism for holding the truck and preventing movement thereof on

the track may consist of a plurality of clamps, each including a shank 25 and a rail-embracing member, fixed to the lower end thereof. This rail-embracing member is generally of inverted U-shape, and includes an upper portion 26 and ends bent inwardly toward each other to form hook-like rail-engaging portions 27, as shown clearly in Figure 4. These rail-engaging portions 27 are somewhat offset from each other and there is a clear passageway between them slightly wider than the width of the head of the rail. When the clamping member is in the position shown in Figure 5, it is apparent that the rail-engaging portions 27 underlie the head of the rail. Vertical or longitudinal movement of the shank 25, when the clamp is in this position, will result in drawing the clamp upward tightly against the head of the rail and will thus anchor the clamp relative to the rail. If the rail-embracing member be turned slightly from the position shown in Figure 5 to that illustrated in Figure 6, it is apparent that the rail-engaging portions 27 will no longer underlie the head of the rail but will have a clear passageway between them which will permit the clamp to be lifted vertically off the rail.

Various mechanisms may be employed for turning the clamp from its effective or Figure 5 position to its ineffective or Figure 6 position and for producing movement of the shank 25 in order to tighten the clamp when it is in the effective position. One possible form of such mechanism, illustrated in the drawings by way of example, comprises screw-threads upon the shank 25 and a nut 30 threaded upon the shank and having worm wheel teeth cut in the periphery thereof. This combined nut and worm wheel 30 is provided with suitable thrust bearings 31 on each side thereof, which allow the worm wheel to rotate freely but which hold it against axial movement relative to the frame of the truck. Rotation of the nut and worm wheel 30 in one direction or the other will therefore result in longitudinal movement of the shank 25 of the clamp. Raising the shank will tighten the clamp if it is in its effective position, shown in Figure 5, but when the clamp is in its ineffective position, as shown in Figure 6, raising the shank will simply pull the rail-engaging portions 27 up past the edge of the head of the rail but will produce no contact between the rail and the clamp.

Any suitable mechanism may be employed for turning the worm wheels 30. Preferably, each worm wheel is driven by a worm 31. Any desired number of clamps may be employed, and the driving arrangements for the worms will obviously depend somewhat on the number and position of the clamps. In the present construction, four of these clamps have been shown, two on each side of the truck to engage each rail. A suitable driv-

ing mechanism for such an arrangement consists of two transverse shafts 32 mounted in the frame of the truck, each shaft carrying two of the worms 31 for cooperation with one of the worm wheels on each side of the truck, as is clearly illustrated in Figure 1. Each of these transverse shafts 32 may be provided at one end with a bevel gear 33 driven by another bevel gear 34 on the end of a jack shaft 35 connected to a suitable motor 36. This motor would preferably be of the reversing type so that it could be used to loosen the clamps as well as to tighten them.

In the construction heretofore described, it will be seen that mechanism is provided for simultaneously driving the various worm wheels to tighten or loosen all the clamps at once. It is obvious, however, that separate driving mechanisms could be employed for each clamp or for each group of clamps, and it is also obvious that the clamps could be tightened or loosened by hand or by any other suitable mechanism without changing the form of the rail-engaging portions of the clamps.

In order to turn the clamps from effective to ineffective position, and vice versa, the shank 25 of each clamp may be provided with a suitable control member, which may be in the nature of a crank plate 37 fixed to each shank near the top thereof and having a crank arm 38 at one side. Each of these control members could be moved independently, but preferably corresponding members on opposite sides of the truck are connected by suitable movement-transmitting means so that movement of one control member results in movement of the other. One possible form of such connection comprises the links or rods 39 connecting a crank arm 38 on one side of the truck with the corresponding arm on the other side, as shown in Figure 1. One of the control members of each pair may be provided with suitable operating means, such as a handle or lever 40 extending out through a slot in the side of the truck so as to be conveniently accessible to the operator. Movement of the handle 40 at one end of the truck controls the two clamps at opposite sides of the truck at that end, while movement of the other handle 40 at the other end of the truck controls the other two clamps, as appears clearly from Figure 1. Thus, it is seen that one pair of clamps may be moved to effective position while the other pair may be placed in ineffective position if it is desired for any reason to clamp the truck at only one end.

It is obvious that the rotation of the worm wheels 30 when moving the clamps upward or downward will tend to produce rotation of the shanks 25 of the clamps, due to the friction between the worm wheel and the shank. Rotation of these shanks may be prevented by means of the same control members 37 which are used to move the clamps to ef-

fective or ineffective position. To accomplish this, a suitable stop member may be employed to hold one of the control members in each pair in one position or the other, and

- 5 thus to overcome the tendency of the clamps to rotate with the worm wheels 30. One possible form of such stop member comprises the pin 41 which may be dropped downward through a suitable hole in the frame of the 10 truck and may enter an opening 42 in one of the control members of each connected pair. This stop member will therefore hold the control member in which it is inserted in the desired position, and because of the link connection 39 between this control member and the other one of the same pair, the other control member also will be held in the same position. When it is desired to move the control members from one position to the other, in order 20 to shift the clamps, the pin 41 may be withdrawn from the opening 42, thus permitting movement of the control member.

It will now be seen that a very simple and effective clamping mechanism has been 25 closed by means of which a truck may be clamped instantly to rails or may be quickly loosened for movement along the track to another position. At the same time, it is but the work of a moment to move the clamps to 30 an ineffective position in which they will not interfere with the entire removal of the truck from the track.

While one embodiment of the invention has been disclosed, it is to be understood that the 35 inventive idea may be carried out in a number of ways. This application is therefore not to be limited to the precise details shown, but is intended to cover all modifications thereof falling within the spirit of the invention or the scope of the appended claims.

I claim:

1. The combination with a truck adapted to run on railway rails, of a clamp for engaging the head of a rail, said clamp including a threaded shank, and being movable from an effective to an ineffective position by turning said shank, and being engageable with the head of a rail by longitudinal movement of said shank when said clamp is in its effective 45 position, a nut threaded on said shank and adapted to produce longitudinal movement thereof when rotated relative to the shank, and a control member fixed to said shank for turning the same from effective to ineffective position and also for preventing the shank from rotating with said nut when the nut is turned to move the shank.

2. The combination with a truck adapted to run on railway rails, of a vertically movable clamp mounted on said truck, said clamp being so arranged that a portion of the clamp will underlie the head of a rail when in one position, and that said clamp is entirely free for vertical separation from said rail when in a second position, means for moving said

clamp from one of said positions to the other of said positions, and separate motor operated means for lowering and elevating said clamp.

3. The combination with a truck adapted to run on railway rails, of a clamp having an oscillatory movement about a vertical axis and engageable with the under face of the head of said rails, said clamp including a member movable longitudinally to tighten the clamp, and a nut threaded on said longitudinally movable member, whereby rotation of said nut moves said member to tighten the clamp.

4. The combination with a truck adapted to run on railway rails, of a plurality of clamps for engaging the heads of said rails, each clamp including a member movable longitudinally to tighten said clamp, a nut threaded on each of said longitudinally movable members, a worm wheel formed integral with each of said nuts, a worm for driving each of said worm wheels, and common operating means for driving said worms.

5. A clamp for engagement with the head of a rail, comprising two rail-engaging portions fixed relative to each other and having a passageway between them wider than the width of the head of a rail, said portions being adapted to underlie the head of a rail when said clamp is in one position, and to permit free vertical withdrawal of said clamp from said rail when said clamp is turned to another position, means for turning said clamp from said first position to said second position, and power operated means for raising and lowering the clamp.

6. A clamp for engagement with the head of a rail, comprising a member of inverted U-shape, the free ends of said member being bent inwardly toward each other, a shank fixed to the central portion of said member, power operated means for moving said shank longitudinally, and means for oscillating said shank about its longitudinal axis.

7. The combination with a truck adapted to run on railway rails, of a plurality of clamps for engaging the heads of said rails, each of said clamps being movable about a vertical axis from effective to ineffective position, a control member associated with each clamp for moving said clamp from one of said positions to the other, movement-transmitting means connecting the control member of one clamp with the control member of another clamp, operating means associated with one of said control members for moving the same, and power operated means for actuating the clamps vertically.

8. The combination with a truck adapted to run on railway rails, of a clamp for engaging the head of a rail, said clamp being movable from effective to ineffective position, mechanism for tightening said clamp when it is in its effective position, said mechanism

- when operating having a tendency to rotate said clamp, a control member associated with said clamp for moving the clamp from effective to ineffective position, and a stop member 5 cooperating with said control member to hold the clamp in its effective position and to oppose said tendency to rotate the clamp.
9. The combination with a truck adapted

to run on railway rails, of a clamp that is movable about a vertical axis to bring it into or out of operative relationship with the rail, and power operated means for moving the clamp vertically to grip or release a rail.

In witness whereof, I have hereunto signed my name.

ALFRED TROSCH.
